UNITED STATES PATENT OFFICE.

ALBERT M. McMILLAN, OF RIVERDALE, MARYLAND.

DESIGN FOR A CLOCK AND WATCH FACE.

54,111.

Specification for Design.

Patented Nov. 4, 1919.

Application filed March 11, 1919. Serial No. 282,047. Term of patent 14 years.

To all whom it may concern:

Be it known that I, ALBERT M. McMILLAN, a citizen of the United States, residing at Riverdale, in Prince Georges county, State of Maryland, have invented a new, original, and ornamental Design for Clock and Watch Faces, of which the following is a specification, reference being had to the accompanying drawing, forming part thereof.

The figure is a view in elevation of a clock or watch face, showing my new design.

I claim:

The ornamental design for a clock and watch face as shown.

ALBERT M. McMILLAN.
